UNITED STATES PATENT OFFICE

CARL HAGEDORN AND JOHN W. HAGEDORN, OF EVERETT, WASHINGTON

GRATE BAR

Application filed January 3, 1929. Serial No. 330,093.

Our present invention relates to improvements in grate bars for use in furnaces of various types, and involving the use of interchangeable, renewable, fuel plates with the supporting parts of the bars. The primary object of the invention is to render more durable the grate bars and extend their period of use by providing venting for the circulation of air currents through the different parts of the grate bars so that the heat may uniformly be distributed to insure uniform expansion and contraction and thus avoid warping or burning of the bars. Means are also provided for relieving the grate bars of excess heat, by the circulation of water through the bars, thus conveying excess heat from the bars and cooling them to such an extent as to prevent warping and burning under excessive heat in the furnace. The invention consists in certain novel combinations and arrangements of parts as will hereinafter be more fully set forth and claimed. In the accompanying drawings we have shown one complete example, and a slight modification thereof, of the physical embodiment of our invention, wherein the parts are combined and arranged according to modes we have thus far devised for the practical application of the principles of our invention, and the grate bars exemplified have successfully and extensively been used, and are now being used in actual practice.

Figure 1 is a view in side elevation of one of the grate bars supported between furnace walls and equipped with the water cooling pipes. Figure 2 is a perspective view of one of the bars with the fuel plates removed, and broken away for convenience of illustration.

Figure 3 is a longitudinal sectional view of a grate bar and its fuel plates, as at line 3-3 of Figure 2.

Figure 4 is a perspective view of one of the fuel plates, inverted, used in Figures 1 and 3. Figure 5 is a transverse vertical sectional view at line 5-5 of Figure 1. Figure 6 is a perspective view of a modified form of fuel plate, inverted, and Figure 7 is a sectional view, similar to Figure 5, but with the water pipes omitted and a modified form of fuel plate illustrated, as shown in Figure 6.

In the preferred form of the invention we have shown in Figure 1 a usual front wall 1, and rear wall or arch 2, of a furnace, the wall or arch 2 being cut away in its front face at 3 to allow for expansion of the grate bars under heat in the furnace. At the front of the furnace a supporting ledge 4 or other suitable support is provided, and a complementary support 5 is used on the front of the arch or rear wall, between which supports the grate bars are supported to permit longitudinal expansion and contraction. 55

Each grate bar includes the hollow member having spaced side walls 6 and 7 that are joined by the integral intermediate webs 8, and the end bars 9, the latter having lateral lugs 10 to space adjoining bars for the formation of vertical slots between the bars to permit venting of air currents through the grate. 60

In the top edge of each of the side walls of the grate we fashion a longitudinally extending groove 11, that is semi-circular in cross section, and extends from end to end of the grate bar, for the reception of water pipes 12 that lie in the grooves. These pipes are connected at their opposite ends to headers or manifolds 13 and 14 at the remote faces of the front and rear walls of the furnace, and the pipes and headers form a circulation system for water 65 throughout the whole grate for cooling the latter or for relieving excessive heat in the bars. The water is supplied to the system through inlet pipe 15 at one end and an outlet pipe 17 is shown at the other end of the system, a control valve 16 being used in the inlet pipe for control of the water flowing through the cooling coils of the grate. 70

In combination with the grate bar we use removable, interchangeable, and renewable fuel plates 18, three of which are shown in Figure 1, but of course more plates are used on a longer grate bar. These plates are concave-convex or arched, with rounded tops, and are provided with holes 19 for venting, and at their undersides each plate is provided with longitudinally extending grooves 20, semi-circular in cross section and complementary to the grooves in the top edges of the walls of the bar. Between the grooved edges of 75

the bar and the grooved edges of the plates the water pipes are enclosed and the pipes provide retaining means for the plates to hold them against lateral displacement. The 5 fuel plates also have side lugs 21 at their opposite ends, complementary to the lugs 10 at the sides of the ends of the bars, and designed to provide for venting slots in the grate between adjoining grate bars.

- 10 On the under face of each fuel plate are a pair of integral lugs 22 and 23 extending transversely of the plate, one lug as 22, being located adjacent an end of the plate while the other lug is located a greater distance from 15 the opposite end of the plate. The length of these bottom lugs is such as to have the lugs fit in between the spaced walls 6 and 7 of the grate and allow for expansion.

In actual practice and extended use of the 20 grate bars with the cooling system of water circulation through the pipes we find that the grate bars are more durable and that they have a greater resistance against warping, burning, or deformation of the fuel 25 plates due to the heat of the furnace. The water pipes are so situated as not to interfere with ventilation through the grate and their enclosure between the grate bars and the fuel plates protects and shields them 30 from direct contact with flames, or with ashes and fuel.

When the presence of the cooling water 35 pipes is not necessary, the fuel plates 18 may be replaced by interchangeable plates 24 from which the semi-circular grooves are omitted, but which are fashioned at their under edges with transversely extending bosses 25 which rest upon the grooved edges at the tops of the side walls 6 and 7 of the 40 grate bar walls, as indicated in Figures 6 and 7 where this modified form of the fuel plates is shown.

It will be noted that the transverse lugs 45 22 are nearer an end of the fuel plate than the lugs 23, and this arrangement of lugs in the series of plates, as in Figures 1 and 3, allows for longitudinal expansion of the plates in the same direction, that is, to the right as in Figure 1. The location of the 50 lugs at different distances from their adjoining edges or ends also prevents likelihood of the plate expanding to such an extent as to wedge the lugs between adjoining intermediate webs or between intermediate webs 55 and adjoining end webs. The fuel plates when worn may thus readily be removed and replaced by fresh ones, the transverse lugs at the under side of the plates being arranged in the same relative positions in each fuel 60 plate.

Having thus fully described our invention, what we claim as new and desire to secure by Letters Patent is—

In a grate bar the combination with spaced 65 side walls having end bars and intermediate

webs, of arched fuel plates having plane faces, transverse bosses on the plane faces resting on said walls and vent openings in the plates, transversely extending lugs on the bottom of the plates between said plane faces, and the lugs on each plate being spaced at varying distances from the ends of the plates.

In testimony whereof we affix our signatures.

CARL HAGEDORN.
JOHN W. HAGEDORN.
